UNITED STATES PATENT OFFICE

2,252,517

BASING MACHINE

Anthony James Marshaus, Cleveland, Ohio, assignor to General Electric Company, a corporation of New York

Application October 20, 1938, Serial No. 300,388

5 Claims.

(Cl. 176—3)

My invention relates to basing apparatus for electric discharge devices, incandescent lamps and like devices.

With the advent of long tubular light sources, such as fluorescent electric discharge lamps recently made commercially available, it has become highly desirable to produce such lamps in a great variety of lengths. The manufacture of the lamps in the different lengths desired has, however, entailed considerable difficulty, particularly as regards the basing operations which require that the lamp be engaged at both ends. Ordinarily, a separate basing machine would be required for each length of lamp, so that a relatively large number of such machines would be required to take care of the maximum production of each type of lamp, although in the ordinary course of events a number of said types would not be in production at any one time. One object of my invention is therefore to provide basing apparatus wherein a single machine will accommodate different types of lamps of greatly different lengths and thereby obviate the need of a large number of such machines. The various lamps usually differ in length in steps of six inches. However, the apparatus comprising my invention may be easily and quickly adjusted to accommodate any desired number of types of lamps varying in lengths of this and even greater magnitude. Other objects and advantages of my invention will appear from the following detailed description of a species thereof, and from the accompanying drawing.

In the drawing Fig. 1 is a plan view of a group of two basing heads and a section through a third, taken on the line 2—2 of Fig. 2, comprising a representative section of basing apparatus embodying my invention; Fig. 2 is a front elevation of one of said heads; and Fig. 3 is a side elevation of a head, partially broken away and in section and on a larger scale.

In the embodiment shown, fluorescent type discharge lamps 10 and pin type bases 11 are held by the basing heads which are mounted at regular intervals at the periphery of a carrier or turret 12. The function of the heads is to hold these parts in proper relation while the cement 13 within the base 11 is heated so that it hardens and secures the base to the lamp envelope.

In the regular order of movement of the turret 12, each head is carried to one station where the lamp 10 and base 11 are inserted therein by an operator who first threads the leading-in wires 14 of the lamp 10 through the pins 15 of the base 11 and then places said base 11 on the end of the lamp. The base 11 comprises, in this instance, a metal shell 16 fastened to a disc 17 of insulating material which supports the metal pins 15, and is provided with a ring of cement 13 which engages both the metal shell 16 and the

reduced end portion 18 of the lamp envelope. A well 19 at the center of the disc 17 provides clearance for the end 20 of the exhaust tube which extends beyond the end of the lamp envelope.

After the base 11 is placed on the lamp 10, the said lamp is moved so that the leading-in wires 14 and the base pins 15 are threaded up through the openings 21—21' (Fig. 1) at opposite sides of a central opening 22' in the holder 21 and the base shell 16 is inserted in the pocket 22 therein. The adjustable holder or cup 23 is then pulled down by manual pressure on the arm 24 until the lower end of the lamp 10 can be moved into position above it whereupon the manual pressure is relieved and said cup 23 moves upward into position to support said lamp 10 and force the base 11 tightly against the holder 21. The cup 23 is mounted on the upper end of the rod 25 which is held by the arms 26—26' extending from the adjustable bracket 26' and is constantly under the influence of the spring 27 which is compressed between the lower of said arms 26 and the block 28 on the rod 25. The arm 24 is attached to the block 28 and enables the block 28 and rod 25 to be adjusted conveniently. Leading-in wires 29 projecting from the lower end of the lamp 10 are bent sideward and upward so as not to interfere with the positioning of the cup 23 below said lamp 10.

Obviously the spring 27 cannot itself compensate for very great differences in the lengths of different lamps, and other means are therefore provided to permit this apparatus to accommodate lamps of different lengths. Two such means are provided in this instance, the first of which provides for the adjustment of the rod 25 and cup 23 with respect to the block 28 and allows the head to be changed to take lamps varying in length, in this particular case, not more than six inches. The block 28 is fastened to the rod 25 by a pin 30 which enters a hole in said rod 25 and screws in said block 28, the said block being thereby repositioned on the said rod 25 by inserting said pin 30 in one of the other holes 31 therein located at spaced intervals therealong. The second adjusting means allows the bracket 26' to be changed to different positions on the channel strip 32 on which it is mounted, and consists of easily separable means for fastening said bracket 26' to the channel strip 32 at varying intervals. The back of the bracket 26' fits loosely in the channel of the strip 32 and is attached thereto by the two large headed pins 33 at the mid point of said back which fit into keyhole slots 34 in said strip 32. The slots 34 are larger at the top to permit insertion therethrough of the heads of the pins 33. Such openings 34 are provided at intervals of six inches in this particular instance and allow the bracket 26' to be ad-

justed vertically several feet. The channel strip 32 is attached to the bracket 35 which supports the holder 21 and is mounted on the turret 12.

The basing operations occur as the head is carried from station to station by indexing movements of the turret 12, and are brought about by burners (not shown) which direct flames onto the outer part of the holder 21. The heat causes the cement 13 to be baked hard in accordance with the usual basing operations. Too much heat applied to the insulating disc 17 would cause it to blister so that the pocket 22 in the holder 21 is relieved over said disc 17 and the base 11 is positioned by engagement of an overlapping rim of the shell 16 which rests on a shoulder in said pocket 22.

A base must also be attached to the opposite end of the lamp 10 and, after completing one revolution of the turret 12, said lamp 10 is removed from the head, provided with a second base and reinserted therein, all as described above. In this case, the leads 29 are inserted in the base pins and the lamp 10 is inverted so that the second base is placed in the holder 21. The excess portion of the leads 14 extending beyond the pins 15 of the base 11 which is already attached to the lamp 10 are cut off before said pins 15 are inserted in the openings 36 in the cup 23 and the base 11 is fitted in the depression 37 therein. As before, the pins of the second base enter openings in the holder 21 and are definitely positioned. The cup 23 also definitely positions the pins 15 of the first base 11, the said cup 23 and the rod 25 being kept from rotating by the engagement of the block 28 with the longitudinal ridge 38 on the bracket 26'. The block 28 is provided with a groove which straddles the ridge 38 so that the pins of the bases at opposite ends of the lamp 10 bear a definite relation to each other. In this case the pairs of pins 15 of both bases are located in the same longitudinal plane passing through the lamp axis. The second base is heated during the rotation of the turret 12 in the same manner as the first, and the based lamp 10 is removed on returning to the loading station.

What I claim as new and desire to secure by Letters Patent of the United States is:

1. In apparatus for securing bases to both ends of elongated electric lamps, a head comprising a fixed holder for a base to be applied to one end of a lamp, an adjustable holder shaped to engage either the opposite end of the lamp or another base thereon for supporting said lamp from its opposite end and positioning it in proper relation to said first mentioned base, a bracket member supporting said adjustable holder and having means thereon for resiliently urging said adjustable holder a limited amount toward said fixed holder, support means for said fixed holder and said bracket member, and means for attaching said bracket member at different positions spaced a considerable distance apart on said support means to permit said head to accommodate various lengths of lamps.

2. In apparatus for securing bases to both ends of elongated electric lamps, a head comprising a fixed holder for a base to be applied to one end of a lamp, an adjustable holder shaped to engage either the opposite end of the lamp or another base thereon for supporting said lamp

from its opposite end and positioning it in proper relation to said first mentioned base, a bracket member carrying means for supporting said adjustable holder so that it is adjustable for small amounts toward or away from said fixed holder and also carrying means for resiliently urging said adjustable holder a limited amount toward said fixed holder, support means for said fixed holder and said bracket member, and means for attaching said bracket member at different positions spaced a considerable distance apart on the said last-named support means to permit said head to accommodate various lengths of lamps.

3. In apparatus for securing bases to both ends of elongated electric lamps, a head comprising a fixed holder for a base to be applied to one end of a lamp, an adjustable holder shaped to engage either the opposite end of the lamp or another base thereon for supporting said lamp from its opposite end and positioning it in proper relation to said first mentioned base, a bracket member carrying said adjustable holder and having means thereon for urging said adjustable holder a limited amount toward said fixed holder, support means for said fixed holder and said bracket member comprising a channel portion for receiving said bracket member and aligning said adjustable holder with said fixed holder, and readily separable engagement means for attaching said bracket member at different positions spaced a considerable distance apart in said channel portion to permit separation of said fixed and adjustable holders to accommodate various lengths of lamps.

4. In apparatus for securing bases to both ends of elongated electric lamps, a head comprising a fixed holder for a base to be applied to one end of a lamp, an adjustable holder shaped to engage either the opposite end of the lamp or another base thereon for supporting said lamp from its opposite end and positioning it in proper relation to said first mentioned base, a bracket member carrying said adjustable holder and having means thereon for urging said adjustable holder a limited amount toward said fixed holder, support means for said fixed holder and said bracket member comprising a channel portion for receiving said bracket member and aligning said adjustable holder with said fixed holder, said channel portion having keyhole shaped slots at spaced intervals therealong, and said bracket member having large headed pins thereon adapted to engage with said slots to permit separation of said fixed and adjustable holders to accommodate various lengths of lamps.

5. In apparatus for securing to each end of an elongated electric lamp a base having a pair of pins thereon, a head comprising a fixed holder shaped to receive a base and to engage the pins thereon to locate the base in a predetermined angular position, said holder also being constructed to permit heating of the base engaged thereby sufficiently to set a quantity of cement in said base, and an adjustable holder shaped to engage either the opposite end of the lamp envelope or another base secured thereon and provided with a pair of pins, said adjustable holder comprising means for engaging the pins on said last-named base to locate the base in a predetermined angular position.

ANTHONY JAMES MARSHAUS.
